UNITED STATES PATENT OFFICE.

WILLIAM JAY, OF LOWELL, MASSACHUSETTS.

SHAVING-BRUSH.

No. 894,834.

Specification of Letters Patent.

Patented Aug. 4, 1908.

Application filed July 9, 1907. Serial No. 382,870.

To all whom it may concern:

Be it known that I, WILLIAM JAY, citizen of the United States, residing at Lowell, in the county of Middlesex and State of Massachusetts, have invented certain new and useful Improvements in Shaving-Brushes, of which the following is a specification.

This invention contemplates certain new and useful improvements in shaving or lathering brushes, and the invention has for its object a simple, hygienic, and efficient construction of shaving brush designed to contain a stick of shaving soap and arranged to feed the same outwardly to the desired extent through the bristles of the brush, so that one's face may be lathered by the direct application of the end of the shaving stick in the moistened bristles.

With this and other objects in view as will 20 more fully appear as the description proceeds, the invention consists in certain constructions, arrangements and combinations of the parts that I shall hereinafter describe and then point out the novel features in the 25 appended claims.

For a full understanding of the invention and the merits thereof and also to acquire a knowledge of the details of construction and of the means for effecting the result, reference 30 is to be had to the following description and accompanying drawings, in which:

Figure 1 is a side elevation of my improved shaving brush; Fig. 2 is a longitudinal sectional view thereof; and, Fig. 3 is a horizontal sectional view of the section being taken on the line 3—3 of Fig. 2.

Corresponding and like parts are referred to in the following description and indicated in all the views of the drawings by the same 40 reference characters.

Referring to the drawing, the numeral 1 designates the tubular body portion of my improved shaving brush, said body portion being constructed of aluminium or other 45 suitably light and strong metal.

2 designates the tubular bristle holding element which is shown in the present instance as integral with one end of the body portion 1. The bristle holding element 2 50 preferably tapers towards its outer end, as shown, so as to produce the proper convergence of the bristles.

3 designates the preferably metallic cap piece of the brush which is preferably hollow 55 as shown, and which preferably screws on the end of the body portion, the latter being

preferably formed with a bead as shown, to limit the movement of the cap piece when it is screwed up to the proper point. The cap piece 3 is formed at its outer end with a recess or socket 4 designed to accommodate the milled or otherwise roughened head 5 of the actuating screw 6, the latter being preferably formed with left hand threads. The screw 6 is provided near the head 5 with a shoulder 7 60 adapted to bear against the outer end of the cap piece, so as to hold the screw properly in place, as it is turned.

A nut 8 works on the screw 6 and a follower head 9 of wood or cork is secured to said nut, 70 the follower head being formed with notch 10 designed to receive the feather or spline 11 which extends longitudinally on the interior of the tubular body portion 1. In addition to its guiding function for the follower head, 75 the spline or feather 11 is designed to retain the shaving stick 12 within the body portion, and for this purpose, the said feather gradually increases in width from the outer or cap end of the brush to the bristle end thereof, so as 80 to retain the shaving stick 12 in place and prevent it from dropping outwardly after it has once been inserted in the body portion. The stick of soap 12 is preferably initially formed with a central longitudinal bore 12^a 85 designed to receive the actuating screw 6.

In the practical operation or use of my improved shaving brush, the shaving stick 12 is inserted within the hollow handle or body portion 1 of the brush and the cap piece 3 is 90 then applied with the follower head 9 and nut 8 at the limit of their movement next to the head 5 of the screw. It is manifest that the soap or stick 12 may then be fed outwardly through the bristles of the brush to 95 the proper extent by merely turning the head 5. The spline or feather 11 is so proportioned with respect to the screw or actuating rod 6 that the said feather will terminate above the follower head or disk 9 when 100 the nut 8 is worked outwardly to the end of the screw. Hence, when this limit of movement is reached, the shaving stick by this time having been used up, it is obvious that the follower disk and nut 8 will merely turn 105 with the screw 6 when the latter is turned, all danger of loosing the follower disk and nut being thereby avoided.

In use, one may dip the tip of the brush in the water and apply it to the beard and by 110 then pressing the brush to the face, the proper quantity of soap may be brought

against the face to give the proper consistency to the lather. The lather may then be worked up on the face by using the end of the brush.

- 5 From the foregoing description in connection with the accompanying drawings, it will be seen that I have provided a very simple, and efficient construction of brush of this character by which the soap may be fed
 10 through the bristles of the brush and which will be hygienic in use, as the lather may be worked up on the face and not in a mug. By the use of my brush, the soap is preserved in good condition and every particle of it may
 15 be used, as the brush handle will also form a handle for the shaving stick until the latter has been entirely used up. At the same time, it is to be noted that the brush forms a very convenient and handy storage receptacle for the shaving stick which will be found of considerable advantage to travelers or campers, and the like, space being thereby economized, and the soap being always at hand when wanted.
 20
 25 For barbers, the device will be found useful, as well as satisfactory to their customers, as it reduces the risk of contagion to a minimum, because the soap is sterilized when the brush is dipped in the hot water to moisten the bristles.

Having thus described the invention, what is claimed as new is:

1. In a brush of the character described, the combination of a tubular body portion
 30 having a uniform cross section throughout its length and adapted to receive a stick of

soap, a cap closing one end of the hollow body portion, bristles at the opposite end of the hollow body portion, a screw held for rotation in the cap and designed to extend 40 through the body portion, a follower disk mounted on said screw and provided in its periphery with a notch, and a longitudinally disposed spline projecting into the interior of the body portion of the brush, the said spline 45 gradually increasing in size as it approaches the bristles and performing the double function of engaging the notch in the follower to prevent rotation thereof, and of embedding itself in the cap so as to prevent the same 50 from falling out of the body portion at the bristle end thereof.

2. In a brush, the combination of a tubular body portion, bristles at one end of the tubular body portion, a cap closing the opposite end of the body portion and having a depression formed therein, an actuating screw passing through the cap, an enlarged head carried by the actuating screw and received within the depression in the cap, a 60 follower mounted within the body portion of the brush and operated by the before mentioned actuating screw, and a spline projecting within the brush body and engaging the follower to prevent rotation of the same. 65

In testimony whereof I affix my signature in presence of two witnesses.

WILLIAM JAY. [L. s.]
